(57) **CLAIM**

The ornamental design for a combined ear muff and glasses, as shown and described.

DESCRIPTION

FIG. 1 is a side perspective view of a combined ear muff and glasses, showing our new design;

FIG. 2 is a top view thereof;

FIG. 3 is a front view thereof;

FIG. 4 is a bottom view thereof;

FIG. 5 is a rear view thereof;

FIG. 6 is a front perspective view thereof, shown in an eye covering position;

FIG. 7 is another front perspective view thereof, shown in an overhead position;

FIG. 8 is a side view thereof, shown in a lowered position;

FIG. 9 is a side view thereof, shown in a raised position;

FIG. 10 is a side view thereof, shown in another raised position;

FIG. 11 is a side view thereof, shown in a first position along the glasses arm;

FIG. 12 is a side view thereof, shown in a second position along the glasses arm; and,

FIG. 13 is a side view thereof, shown in a third position along the glasses arm.
